UNITED STATES PATENT OFFICE.

GEORGE H. RICE, OF GREEN BAY, WISCONSIN.

LUMBER-STACKER.

1,108,520.

Specification of Letters Patent. Patented Aug. 25, 1914.

Application filed September 22, 1913. Serial No. 791,127.

To all whom it may concern:

Be it known that I, GEORGE H. RICE, a citizen of the United States, and resident of Green Bay, Brown county, Wisconsin, have invented certain new and useful Improvements in Lumber-Stackers, of which the following is a specification.

In the piling or stacking of lumber for drying purposes, it has been usually necessary to employ the services of at least two men—one to stand on the pile and the other to pass the lumber up from the ground or from a load.

The object of my invention is to provide an apparatus by means of which lumber may be stacked to any desired height and handled by one man on the pile.

A further object is to provide an apparatus by means of which lumber may be stacked more rapidly and with less labor than by the usual method.

Other objects of the invention will appear from the following detailed description.

The invention consists generally in various constructions and combinations all as hereinafter described and particularly pointed out in the claims.

In the accompanying drawings forming part of this specification. Fig. 1 is an end elevation of a lumber-stacking apparatus embodying my invention, Fig. 2 is a side elevation of the same, Fig. 3 is a detail view of a portion of the apparatus, Fig. 4 is a view showing in detail the device for plumbing the pile of lumber as it is stacked, Fig. 5 is a sectional view on the line $x-x$ of Fig. 3, Fig. 6 is a detail view of the frame forming a portion of the lumber sling.

In the drawing, 2 represents a suitable track running through the lumber yard, and 3 and 4 are upright standards having wheels 5 adapted to run on said track and connected at the top and bottom by suitable cross bars or braces 6 and 7. The standards are also braced at other points to form a rigid, erect tower or frame. These standards may be composed of suitable material and the frame is of sufficient height to adapt it for stacking the lumber as high as may be desired.

Centrally mounted in the top of the tower is a rail 8 on which an electric hoist 9 is supported and adapted to slide lengthwise of the rail to adjust it for the desired hoisting position. This rail

preferably extends outwardly beyond the tower on each side thereof to allow a wide range of movement of the hoist. A sling frame 10 is supported by a cable 11 from the hoist and has sling chains 12, which are adapted to pass under the load of lumber 13 resting upon the wagon 14. A lumber support or rest, consisting preferably of a bar 15 has slots 16 in the ends thereof to receive the flanges of the upright standards 4 and pins 17 are mounted at intervals in these standards in position to support bars 18 mounted to slide longitudinally of the bar 15 and pivotally connected to one another by links 19 which are eccentrically connected with a disk 20 having an operating handle 21. When this disk is rocked, the bars 18 will be withdrawn or projected to engage the supporting pins 17 or become disengaged therefrom. The bar is raised to the desired elevation by means of cables 22 having running connections with pulleys 23. By means of these cables the bar 15 may be adjusted to the desired elevation for stacking lumber. When the load of lumber has been raised to the desired elevation, it is swung upwardly until one end overhangs the bar 15 and the hoist is then slackened sufficiently to allow the end of the pile of lumber to rest on the bar, preparatory to stacking the lumber. Suitable cables 24 connect the frame 10 with the lower portion of the standards and prevent the load of lumber from sliding off the supporting bar.

I prefer also to provide on each side of the apparatus a device for aiding the workman in plumbing the pile of lumber. This device consists of a triangular frame 25, hinged at 26 on the carrier bar 15 and having bars 27 pivoted to the triangular frame 25 at 28 and adapted to bear on the standards 3 or 4, said bars being connected transversely with one another by braces 29. Ears 30 are mounted on the frame 25 and have adjusting screws 31 to engage the bars 27 and enable the operator of the apparatus to tilt the frame 25 and adjust it for a vertical position or at a slight angle to the vertical. This frame 25, of which there is one on each side of the machine, moves up and down with the bar 15 and forms a stop for the ends of the boards or other lumber that is being stacked and enables the workman to easily and quickly aline the ends of the pieces of lumber and facilitates to a considerable degree, the stacking of the pile.

Cables 22' are attached to the bars 27 and have running connections with pulleys 28'. By means of these cables the operator can draw the bars 27 against the standards of the tower and against the adjusting screws 31. As indicated in Fig. 1, the bars 27 may be dropped down to a substantially vertical position, where the frame 23 will rest against the upright standards until needed again.

For convenience in moving the frame or tower from place to place, I prefer to provide a motor 32, geared to a shaft 33 which has belt connections 34 with pinions 35 that mesh with gears 36 on the axles of two of the opposite wheels supporting the tower. When the motor 32 is set in motion, the tower may be moved along the track from place to place in the yard.

I claim as my invention:—

1. A lumber stacking apparatus comprising a tower, a lumber sling and hoist carried by said tower, and movable horizontally therein from one side to the other of said tower, and a vertically adjustable lumber rest adapted to support the adjacent end of the lumber carried by said hoist.

2. A lumber stacking apparatus comprising a tower, a lumber sling and hoist therefor, a vertically adjustable bar arranged to support one end of the lumber in said sling, and a lumber plumbing device movable vertically with respect to said tower.

3. A lumber stacking apparatus comprising a tower, a lumber sling and hoist there-

for, a lumber rest vertically movable in said tower and adapted to support one end of the lumber in said sling, a lumber plumbing device supported by said rest and comprising a hinged frame and bars pivotally connected with said frame and having a bearing on said tower.

4. A lumber stacking apparatus comprising a tower, a lumber sling and hoist mounted thereon, a rest adapted to support one end of the pile of lumber in said sling, reciprocating bars mounted in said lumber rest means for operating the same, and pins arranged one above another in said tower and adapted to engage and support said bars and rest.

5. A lumber stacking apparatus comprising a tower, means for hoisting the pile of lumber to the desired elevation in said tower, and a vertically movable lumber plumbing device carried by said tower.

6. A lumber stacking apparatus comprising a tower, a lumber sling and hoist carried by said tower and movable horizontally therein from one side to the other of said tower, and a lumber rest carried by the legs of said tower and vertically adjustable thereon and adapted to support the adjacent end of the lumber carried by said hoist.

In witness whereof, I have hereunto set my hand this 28th day of August 1913.

GEORGE H. RICE.
